UNITED STATES PATENT OFFICE

134,828

DESIGN FOR A CLOSURE FOR GASOLINE CONTAINER

Letcher O. Grice, United States Army
Washington, D. C.

Application May 2, 1942, Serial No. 106,777

Term of patent 3½ years

To all whom it may concern:

Be it known that I, Letcher O. Grice, United States Army, a citizen of the United States, residing at Washington, District of Columbia, have invented a new, original, and ornamental Design for a Closure for Gasoline Container, of which the following is a specification, reference being had to the accompanying drawing, forming part thereof.

Fig. 1 is a perspective view of a closure for gasoline container, showing my new design, and Fig. 2 is a top plan view thereof.

I claim:

The ornamental design for a closure for gasoline container, as shown.

LETCHER O. GRICE.
